UNITED STATES PATENT OFFICE.

CÉLESTIN HERBLINE, OF PARIS, FRANCE.

FIRE EXTINGUISHER OF THE LIQUID TYPE.

No Drawing. Application filed November 6, 1925, Serial No. 67,446, and in France November 10, 1924.

It is observed that the known fire extinguishers are defective from the fact that phosgen is disengaged at the time of use, and due to its toxic nature, the use of fire extinguishers of the liquid type for aviation or for naval purposes, or the like, has been discontinued.

My invention relates to a fire extinguisher of the liquid type wherein the aforesaid defect is obviated, i. e. the phosgen is entirely eliminated, and I am further enabled to form a fireproof layer at the place upon which the contents of the extinguisher are directed, thus preventing the fire from breaking out again at that point when the extinguishing liquid is volatilized, this latter effect being also made rapid.

In a general manner, I add to the usual extinguishing liquid itself, such as tetrachloride of carbon, trichloroethylene, tetrachlorethane or the like, a suitable amount of a substance or a mixture of substances, indicated as follows:

1. Fatty substances.
2. Hydrocarbons of the aromatic series.
3. Sulphochloride of thiocarbonyl.
4. Tetrachlorosulphide of carbon.

1.—Among the fatty substances, I may employ for instance the fatty acids, animal or vegetable grease, animal or vegetable oil (sulphonated or not), or the sulpho-ricinates, as well as their solutions, mixtures, or combinations, and such substances will also lubricate the frictional parts of the apparatus, while at the same time exercising a physical action consisting in the formation of a sort of coating upon the burning bodies whereby the extinguishing liquid is maintained in contact with the same.

2.—As to the hydrocarbons of the aromatic series, I may employ the benzenic carbides and their derivatives, the pyrogenated hydrocarbons (naphthalene, anthracene, etc.) and their derivatives; also their solutions, mixtures or combinations, which will further act as absorbents for toxic gas or vapours.

3.—Sulphochloride of thiocarbonyl. I may employ its solutions, mixtures or combinations.

4.—Tetrachlorosulphide of carbon (with traces of iodine or not). The solutions, mixtures or combinations of this body may be used.

For the composition of an extinguishing liquid according to my invention, the following substances are given by way of ex-

ample, but the proportions are not of a limitative nature:

	Kgs.
Tetrachloride of carbon	160 60
Sulpho-ricinate of sodium	1 to 2
Naphthalene	1 to 25

It should be noted that with the known extinguishing liquids, suitable substances must be added thereto in large proportions (this being a difficult operation) in order to eliminate the phosgen, but this causes the formation of a deposit which is prejudicial to the functioning of the apparatus discharging such products.

In my apparatus, I employ but a small proportion of the above-mentioned substances or mixtures of substances; these will not produce vapours of a dangerous nature and capable of attacking the apparatus containing the liquid. Even after a long period, they will not form deposits which clog up the apparatus and hinder its operation.

It should be observed that among the aforesaid bodies which are mixed with the extinguishing liquid itself, certain of these will only perform their functions after having remained for a sufficient time in contact with the extinguishing liquid.

Having now particularly described and ascertained the nature of my said invention and in what manner the same is to be performed, I declare that what I claim is:

1. A fire extinguishing liquid which will not form phosgene at the time of its projection, consisting essentially of an extinguishing liquid in mixture with a fatty substance.
2. A fire extinguishing liquid which will not form phosgene at the time of its projection, consisting essentially of an extinguishing liquid, a fatty substance, and a polynuclear aromatic hydrocarbon.
3. A fire extinguishing liquid which will not form phosgene at the time of its projection, consisting essentially of carbon tetrachloride, sodium sulpho-ricinate, and naphthalene.
4. A fire extinguishing liquid which will not form phosgene at the time of its projection, consisting essentially of 160 parts of carbon tetrachloride, 1 to 2 parts of sodium sulpho-ricinate, and 1 to 25 parts of naphthalene.

In testimony whereof I affix my signature.

CÉLESTIN HERBLINE.
